SHEET PLASTIC FABRIC

Philip Schuss, Columbus, Ohio, assignor to Columbus Coated Fabrics Corporation, Columbus, Ohio, a corporation of Ohio

Application May 8, 1958, Serial No. 50,810

Term of patent 3½ years

(Cl. D87—3)

The figure is a plan view of a sheet plastic fabric showing my new design. The dot and dash lines of the drawing outline a design unit, which unit is repeated in regular succession, as indicated by the extensions beyond the unit boundary.

I claim:

The ornamental design for a sheet plastic fabric, substantially as shown and described.
